UNITED STATES PATENT OFFICE.

CHARLES McGINN, OF HARTFORD, CONNECTICUT.

DESIGN FOR A BOTTLE.

SPECIFICATION forming part of Design No. 29,060, dated July 19, 1898.

Application filed October 9, 1896. Serial No. 608,418. Term of patent 14 years.

To all whom it may concern:

Be it known that I, CHARLES McGINN, a citizen of Great Britain, residing at Hartford, in the county of Hartford and State of Connecticut, have invented and produced a certain new and original Design for Bottles; and I do declare the following to be a full, clear, and exact description of the invention, such as will enable others skilled in the art to which it appertains to make and use the same.

My invention relates to a new and original design for a bottle; and it consists of a bottle of the shape and configuration shown in the accompanying drawings.

Figure 1 is a side elevation of the bottle, and Fig. 2 is a longitudinal sectional view.

The leading or characteristic features of the design reside in a bottle of the shape shown, having a neck formed with an annular downwardly and outwardly projecting bulged lobe 2, which lies in a plane below that of the outlet of the neck and is integral with said neck

and surrounds a portion of its length, said lobe extending upwardly and inwardly over the mouth of the bottle and provided with a central aperture 4, which is of greater diameter than the opening in the neck of the bottle and is of a diameter corresponding to the outside diameter of said neck, said inwardly projecting portion or that portion which extends over and above the neck being flattened or straight for a distance equal to the outside diameter of the neck, while the remaining portion of the lobe is distinctively curved or rounded throughout its entire area.

What I claim is—

The design for a bottle as herein shown and described.

In testimony whereof I hereunto affix my signature in presence of two witnesses.

CHARLES McGINN.

Witnesses:

JOHN W. COOGAN,
EDWARD J. GARVAN.
